UNITED STATES PATENT OFFICE.

BURDON P. HYDE, OF WATERBURY, CONNECTICUT, ASSIGNOR TO SCOVILL MANUFACTURING COMPANY, OF WATERBURY, CONNECTICUT, A CORPORATION OF CONNECTICUT.

COSMETIC-STICK HOLDER.

Application filed February 12, 1924. Serial No. 692,285.

To all whom it may concern:

Be it known that I, BURDON P. HYDE, a citizen of the United States, residing at 61 Church Street, Waterbury, county of New Haven, and State of Connecticut, have invented certain new and useful Improvements in Cosmetic-Stick Holders, fully described and represented in the following specification and the accompanying drawings forming a part of the same.

This invention relates to certain improvements in holders for cosmetic preparations, such as lipsticks, facial greases and the like, in which the cosmetic is applied by rubbing the cosmetic stick on the part of the person to which it is desired to apply the cosmetic.

It is the special object of the present invention to provide an improved dispensing holder for cosmetic sticks, in which the stick may be propelled beyond the holder for applying the cosmetic and retracted within the holder when not in use, the parts being designed so that they can be readily and quickly assembled and in which a positive propelling action for the stick in either direction is effected without danger of the parts getting out of order.

The further object of the invention is to provide such a holder which will be compact, of attractive appearance, and which can be readily manipulated for use.

With these and other objects not specifically referred to the invention consists in certain parts, arrangements and combinations which will be fully described in connection with the accompanying drawings, and the novel features pointed out in the claims hereunto annexed.

In these drawings—

Figure 1 is a side view of an improved holder.

Figure 2 is a vertical sectional view partly broken away on an enlarged scale.

Figure 3 is a further vertical sectional view, the section being taken on line 3—3 of Figure 2.

Figure 4 is a cross-sectional view taken on line 4—4 of Figure 3.

Figure 5 is another cross-sectional view taken on line 5—5 of Figure 3.

Figure 6 is a sectional side elevation of the outer casing.

Figure 7 is a similar view of the inner or rotary casing.

Figure 8 is a side view of the stick carrier; and

Figure 9 is a perspective view of one connection which may be employed for connecting the stick carrier and the propelling devices.

Referring now to these drawings, the improved holder will include an outer casing or barrel 1, preferably of light metal, which may be of any desired size but which is in best constructions small, so as to be conveniently carried in a hand bag, vanity case or the like. This barrel is open at its lower end as indicated by a numeral 2, and at its upper end is formed with an inturned shoulder 3, and an opening 4 with which a member hereafter referred to co-operates to form a discharge orifice. Near its upper end also the casing or barrel 1 is provided with a rim or bead 5, this bead acting as a stop for the lower edge of a cap 6 by which the barrel may be closed.

Located within this barrel is a stick carrier shown in the form of a cup 7 closed at its bottom and open at its top, this cup being adapted to receive one end of a stick 8 of any desired cosmetic or toilet preparation. This carrier is projected beyond the barrel for use, and withdrawn into the barrel for non-use, a propelling means of improved construction being provided for effecting this. While the specific construction of the carrier propelling devices may be somewhat varied, in the particular construction illustrated the carrier is given a simultaneous longitudinal and rotary motion in the holder. As shown the carrier is contained in a tube or casing 10, which tube at its lower end is closed and has fixedly secured thereto, as by a rivet 11, a finger piece or cap 12, by which the tube may be rotated. This cap as shown at 13 in Figure 7 is spaced from the outer wall of the tube 10 so as to permit the insertion of the lower end of the barrel 1 in this space, the tube thus being rotatable with respect to the barrel.

The tube 10 is formed on one side with a narrow longitudinal slot 14, and surrounding the tube is a helix or spiral screw, this helix being preferably stationary relatively to the tube. While this helix may vary widely in construction, in its best form, it will comprise a spiral formed of

a small size spring wire, as with such construction it is unnecessary to cut screw threads, which is difficult in the thin metal of which the parts are made. Furthermore this spring acts to hold the parts together, and prevents them from getting out of position when the holder is manipulated.

Connections are provided between the stick carrier 7 and the spring so that as the 10 tube 10 is rotated the carrier will ride on the spring in either direction, and in the best constructions this connecting means will be, for ease in assembly, an independent piece or part.

15 In the particular construction shown the carrier 7 is provided with a narrow slot 15 in its side, and the connection will include a key member having a nose 16 dimensioned to fit the slot 15. On the side or face of the 20 connecting member opposite the nose there are provided two projections 17 between which is formed a groove or recess 18 dimensioned to receive the spring helix 19. With this construction the parts are readily 25 assembled, it being necessary simply to bring the slots 15 and 14 into alignment, drop the connecting member into position in the slot 15 and wrap the helix about the tube. The spring is prevented from rotating by inserting its lower end 20 in a 30 notch or slot 21, see Figure 3, formed in the lower extremity of the wall of the barrel 1.

In the best constructions a stop is provided for limiting the upward movement 35 of the stick carrier. While this may be done in various ways as shown it is conveniently effected by turning down the upper end of the wire as indicated at 22 in Figure 2, the hook thus formed projecting across the slot 14 affording a stop against which the connecting member will abut when the parts are in extreme projected 40 position.

45 Provision is made for preventing the tube from being withdrawn outwardly from the barrel. As shown this is done by slightly flaring out the upper edge of the tube 10 as indicated at 23 in Figure 3, this flaring 50 edge 23 lapping over onto the flange 3 of the barrel 1 before referred to, this flaring of the tube 10 being done after the parts are assembled.

As shown, where the cap 12 is secured to 55 the tube 10 by a rivet, the central part of the cap will be slightly inset as indicated at 24 in Figure 7, so that the holder will stand upright on any support when desired without tipping or rocking.

60 With the construction shown and described it will be seen that a simple holder of few parts has been provided and one in which the parts may be readily and quickly assembled, and in which because of the absence of screw threads very light metal may

be used thus providing a holder of very little weight and one which is very economical to manufacture. Although the invention has been shown in its preferred form it will be understood that various changes may be 70 made in the construction and arrangement of the parts without departing from the invention as defined in the claims hereunto annexed.

What I claim is:

75 1. In a cosmetic stick holder, the combination with an outer casing, of a rotatable tube having a longitudinal slot therein positioned within said casing, a slotted stick carrier positioned within said rotatable 80 tube, a helix loosely supported within the outer casing, and a loose key member extending through the slots in the stick holder and rotatable tube, said key member being provided with a helix engaging portion 85 and a portion arranged to positively engage and hold a stick in said holder.

90 2. In a cosmetic stick holder, the combination with an outer casing, of a rotatable tube having a longitudinal slot therein positioned within said casing, a slotted stick holder positioned within said rotatable tube, a helix consisting of a spring surrounding said rotatable tube, said spring having one end anchored to the outer casing, and a loose 95 key member arranged to extend through the slots in the stick holder and the rotatable tube, said key member having a helix-engaging recess at one end thereof and a nose portion arranged to positively engage and 100 hold a stick in said stick holder.

105 3. In a cosmetic stick holder, the combination with an outer casing, of a rotatable tube having a longitudinal slot therein positioned within said casing, a slotted stick holder positioned within said rotatable tube, a helix consisting of a spring surrounding said rotatable tube, said spring being anchored to the outer casing and having a free end over-hanging the slot in the rotatable tube and bent to form a stop, a loose key member arranged to extend through the slots in the stick holder and the rotatable tube, said key member having a helix-engaging portion at one end and a stick-engaging portion at its opposite end, and a removable cap covering the end of said casing.

110 4. In a cosmetic stick holder, the combination of an outer casing having an in-turned flange surrounding an opening at one end thereof, a rotatable tube having a longitudinal slot positioned within said casing, said tube having its end flared to overlie said inturned flange, a slotted stick holder positioned within the rotatable tube and arranged to move longitudinally with respect thereto, a helix stationarily supported within the outer casing, and a loose key member extending through the slots in the 115 120 125 130

stick holder and rotatable tube, said key member having a helix-engaging recess.

5. In a cosmetic stick holder, the combination with an outer casing, of a rotatable tube having a longitudinal slot therein positioned within said casing, a slotted stick holder positioned within said rotatable tube, a helix consisting of a spring loosely surrounding said rotatable tube, said spring 10 being anchored to the outer casing at one end and having its other end overhanging said slot in the rotatable tube and bent to

form a stop, a loose key member having an intermediate portion arranged to lie in the slots in the stick holder and rotatable tube, said key member having a helix-engaging portion and a stick-engaging portion at opposite ends thereof, and a cap secured to the rotatable tube for turning the latter relatively to the outer casing. 15

20 In testimony whereof, I have hereunto set my hand.

BURDON P. HYDE.
